UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,557, dated January 7, 1890.

Application filed December 10, 1889. Serial No. 333,284. Term of patent 3½ years.

To all whom it may concern:

Be it known that I, WILLIAM K. BENEDICT, of New York, in the county and State of New York, have invented and produced a new and 5 original Design for the Exterior of a Residence, of which the following is a specification, reference being had to the drawings forming a part thereof.

Figure 1 represents a front elevation of a 10 residence showing my design. Fig. 2 represents a plan view of the first story. Fig. 3 represents a plan view of the second story. Fig. 4 is a side elevation of a residence showing my design.

15 Similar letters of reference designate corresponding parts in all the figures.

The first story of the residence upon the front discloses a door A, surmounted by an 20 arc-shaped window a. Above the arc-shaped window is an arc-shaped lintel a'. Pilasters a² are shown as supporting the arc-shaped lintel a'. At one side of the door A is a window B, which window is shown as having an arc-shaped upper portion b. Above the arc-shaped portion b is an arc-shaped lintel b'. The second story of the front is illustrated as 25 having two windows C, each of which has an arc-shaped upper portion c. Above the arc-shaped portion c of the windows are arc-shaped beads c'. Above the arc-shaped beads c' is a cornice D, comprising a molding d', and above the molding machicolation d'.

Above the machicolation d' is a molding d². A flight of steps E leads up to the porch A. The side of the residence illustrates on the 35 first story a window F, having an arc-shaped upper portion f, and above the arc-shaped portion a beading or molding f'. Above the window F on the second story is a window G, somewhat smaller than the window F, but 40 corresponding in shape thereto, and having above it an arc-shaped bead or molding g. The cornice above the second story (shown in Fig. 4) is upon the side of the residence machicolated, like that shown upon the front of 45 the residence, and has the beading g' below said machicolation and a beading g² above it. At the rear of the residence is an extension II. This extension is illustrated as having upon one side a cornice I, which cornice comprises a molding i, and above the molding 50 consoles i². To the rear of the windows F G in the main portion and upon the side are substantially rectangularly-shaped windows J, and upon the extension II to the rear of the 55 windows J are substantially rectangularly-shaped windows K.

What I claim is—

A design for the exterior of a residence, substantially as herein shown and described. 60

WILLIAM K. BENEDICT.
